UNITED STATES PATENT OFFICE.

BENJAMIN CARDENAS REYES, OF SAN ANTONIO, TEXAS, ASSIGNOR OF ONE-HALF TO
MAURICE J. ROOS, OF SAN ANTONIO, TEXAS.

TROUSERS.

1,380,681.

Specification of Letters Patent. Patented June 7, 1921.

Application filed November 21, 1919. Serial No. 239,533.

To all whom it may concern:

Be it known that I, BENJAMIN CARDENAS REYES, a citizen of the United States, residing at San Antonio, in the county of Bexar and State of Texas, have invented certain new and useful Improvements in Trousers, of which the following is a specification.

The object of this invention is to provide simple and efficient means for altering 10 ready-made trousers to fit persons of different sizes.

Ready-made trousers rarely fit persons of approximately the same age or size, and alterations are often required before the 15 trousers are delivered. When ready-made trousers are completed, *i. e.*, all seams are sewn, it is necessary to rip some of the seams and readjust the folds of the goods where the 20 seams are made in order to widen or shorten the body portion of the trousers at the waist and for some distance below the 25 waist-band. Furthermore, sufficient material is not always provided for obtaining the necessary adjustments.

According to my invention, I provide 30 ready-made trousers with openings at the sides immediately in rear of the side pockets which extend through the waist-band and for a short distance below the bottom of 35 the side pockets, and I provide material on opposite sides of these seams sufficient in extent to give any desired width to the body portion of the trousers before the goods is folded to bring together the edges of the 40 seams and before the stitching operation is performed.

In order to provide still further adjustments, I form an opening of similar construction to those before described in the 45 back of the body portion of the trousers, by means of which adjustments in connection with the adjustments at the sides may be obtained which will provide a neat and well-balanced fit of the trousers in the body portion thereof.

In the accompanying drawings:—

Figure 1 is a perspective view of the upper portion of a pair of trousers, embodying my improvements after the adjustments 50 have been made and the seams stitched.

Fig. 2 is a perspective view of the upper portion of a pair of trousers embodying my improvements, showing the construction before the adjustments have been made and 55 the seams sewn.

Fig. 3 is a detail view, illustrating the construction of one of the side seams.

The upper portion of the trousers is indicated at B, *b* being the front and *b'* the rear or seat part. *x* indicates the side seams 60 placed in the usual way, and C indicates the side pockets. E indicates the waist-band.

Trousers made in accordance with my invention have the side seams of the legs sewn from the bottom upward to the point *x* a 65 considerable distance below the bottom of the side pockets. From this point upward there are openings and these openings extend through the waist-band, as indicated in Fig. 2. Sufficient material is provided at 70 *z* in the waist-band and in rear of the side pockets to permit the goods to be turned or folded in the manner shown in Fig. 1 in order to provide a folded part to be secured to a corresponding part on the opposite side 75 of the seam.

In Fig. 3, *g* indicates a creased part at the inner edge of a flap G which provides material for widening or reducing the girth of the trousers at the waist and for a considerable distance below it. The flap G extends from the top of the waist-band to the bottom of the opening. When a pair of trousers is being fitted to a customer, the flap G on each side is folded along the 80 proper line, temporarily held in place by pins or stitching, and then sewn at *h*, in the manner shown. In this way a good fit is quickly obtained with very little trouble and at the same time a neat job is secured. 90

In some cases it is desirable also to adjust the waist of the trousers in the rear. This may be done by an opening which extends through the waist-band to a considerable distance, namely, to the point *m*, indicated 95 in Fig. 2. Flaps *m'*, *m*² are provided to permit of the desired adjustments and then the folded parts on opposite sides of the opening are sewn together in the manner indicated.

Ordinarily when trousers having no special provision for alteration are changed to fit a customer the general fit of the trousers is so altered as to throw them out of balance and to be generally unsatisfactory. 105 Often trousers are altered at the back only, but this does not produce the desired results. Trousers as ordinarily made have no special provision for altering them at the sides and if it is attempted to so alter them 110.

- at the sides skilled labor is required and much time is consumed. When fitting a man with a large chest and small waist, alterations at the sides of the trousers give the best results, otherwise the legs of the trousers would twist and the hip pockets would approach each other to an undesirable extent while the side pockets would be moved to positions too far in rear of the hip bones.
- 10 When fitting a man with a small waist and large hips, the trousers should be made larger at the hips to give full hip effect. If the alteration were made in the back seam only a loose seat would be produced and no alteration in the hip parts of the trousers would be effected. Furthermore, when the trousers are made smaller in the back, not only are the legs twisted but the trousers are made to draw unduly over the abdomen.
- 15 By my improvements where openings of the kind described are provided at the sides of the trousers, the objections to the usual method of alteration are avoided and the trousers when finished, when made larger or smaller, are nicely balanced and a satisfactory fit in all particulars is obtained.

As indicated in the drawings, the edges of the flaps *e*, *G*, are preferably provided with a binding, indicated at *y* in Fig. 3, and also shown in other figures of the drawings. This, however, is not essential. The flaps

at the back of the trousers may also be provided with a binding, as shown.

It will be observed that the upper portion of the trousers is made in four sections and *ss* that there are waist-band lining sections extending along the upper edge of each of said four sections to the vertical edges thereof.

I do not claim as my invention, such as a pair of trousers, having its upper *ss* portion made in four sections, waistband lining sections extending along the upper edge of each of said four sections to the vertical edges thereof.

I claim as my invention:—

45 Trousers, comprising a body portion provided with side pockets and a waist-band, the lower portion of the body having side seams sewn upward to points a considerable distance below the bottom of the side pockets and having openings extending in rear of the side pockets through the waist-band, said openings being each provided on its side next the side pocket with sufficient material to be turned and on its opposite 50 side with a flap of considerable width adapted to be folded on various lines to adjust the width of the waist-band and the body of the trousers in rear of the side pockets.

In testimony whereof, I have hereunto 55 subscribed my name.

BENJAMIN CARDENAS REYES.
